SHEET HANDLING MECHANISM FOR WEB PRINTING ROTARY PRESSES

Howard M. Barber, Pawcatuck, Conn., assignor to C. B. Cottrell & Sons Company, Westerly, R. I., a corporation of Delaware

Application April 30, 1936, Serial No. 77,140

2 Claims. (Cl. 271—79)

The object of my invention is to cut sheets from a traveling web and to collect the sheets at the speed of the press and to finally deliver the so collected sheets flat upon inner and outer piles at a lesser speed for ensuring the proper deposit 5 of the sheets upon the said piles.

My invention comprises, generally, means for severing the sheets from the traveling web, means for collecting the sheets and means for delivering the sheets, said delivery means comprising inner 10 and outer endless carriers arranged to take the sheets from the collecting means and to deposit the sheets upon their respective inner and outer delivery piles.

My invention comprises, more specifically, 15 sheet transfer and collecting rotary carriers, a sheet transfer endless carrier traveling at the surface speed of the transfer and collecting rotary carriers and having suitably spaced grippers for taking the sheets from the sheet collecting 20 rotary carrier, and a sheet delivery endless carrier traveling at a lesser surface speed and having spaced grippers for taking the collected sheets from the inner endless carrier grippers and depositing the sheets upon their respective inner 25 and outer delivery piles.

A practical embodiment of my invention is represented in the accompanying drawing, in 30 which the figure illustrates in diagrammatic side elevation so much of a mechanism for cutting, collecting and delivering sheets, as includes my invention.

The traveling web which is denoted by 1 passes 35 between rotary cutters 2, 3, where the sheets are severed from the traveling web by the coacting cutter blades 4, 5.

The web then passes between guide rolls 6, 7 to a sheet transfer rotary carrier 8 having two sets of diametrically opposed grippers 9. A pressure roller 10 serves to ensure the grasping of 40 the leading edge of the web by one of the sets of grippers 9 as the sheet is severed from the web.

The sheet collecting rotary carrier 11 has 45 three sets of equally spaced grippers 12 arranged to take successive sheets from the transfer rotary carrier grippers 9 and collect the sheets on the three surfaces of the said rotary carrier 11. The sheet transfer rotary carrier 8 is shown as two-thirds the size of the sheet collecting rotary carrier 11 so that the sets of grippers 12 on both rotary carriers are spaced the same distances apart around their respective carriers.

The delivery for the collected groups of sheets 50 is constructed, arranged and operated as follows:

A horizontally disposed sheet transfer carrier

13 travels in an endless path, its inner end being located beneath the sheet collecting rotary carrier 11, which endless carrier 13 comprises the usual side chains which pass around the inner and outer end sprockets 14 and 15 respectively. This sheet transfer endless carrier is provided in the present instance with two sets of grippers 16 spaced the required distance apart.

A horizontally disposed sheet delivery carrier 17 travels in an endless path, its inner end being located over the outer end of the sheet transfer 10 endless carrier 13, which endless delivery carrier comprises the usual side chains which pass around the inner and outer end sprockets 18 and 19 respectively. This sheet delivery endless carrier 17 is provided in the present instance with 15 six sets of grippers 20 spaced the required distances apart.

Inner and outer delivery piles 21 and 22 are located beneath the sheet delivery endless carrier 17 in position to receive the groups of 20 collected sheets from the said endless carrier 17.

The sheet transfer rotary carrier 8, the sheet collecting rotary carrier 11 and the sheet transfer endless carrier 13 are all driven at substantially the same surface speed. The sheet delivery 25 endless carrier 17 is driven at a slower surface speed. The means which I have shown for accomplishing this result is as follows:

A gear 23 on the shaft of the sheet collecting 30 rotary carrier 11 is operatively connected through a pinion 24 with a gear 25 on the shaft of the inner sprocket 18 of the sheet delivery endless carrier 17. This gear 25 is operatively connected through the pinions 26 and 27 with a gear 28 on 35 the shaft of the outer sprocket 15 of the sheet transfer endless carrier 13.

The grippers on the several rotary and endless carriers are operated to cause the grippers 9 on the sheet transfer rotary carrier 8 to take the 40 successive sheets which are cut from the traveling web and transfer them to their respective grippers 12 on the sheet collecting rotary carrier 11, where the sheets are collected and transferred to the grippers 16 of the sheet transfer 45 endless carrier 13. These grippers 16 in turn transfer the groups of sheets to their grippers 20 on the slower traveling sheet delivery endless carrier 17, which grippers 20 are released at the proper times for delivering the groups of sheets 50 to their respective delivery piles.

Coacting cams 29 and 30 serve to operate the coacting sets of grippers 9 and 12 to cause the transfer of the sheets to the sheet collecting rotary carrier 11. Coacting cams 31 and 32 serve 55

- to operate the grippers 12 and 16 to cause the groups of collected sheets to be transferred at the proper times from the sheet collecting rotary carrier 11 to the sheet transfer endless carrier 13.
- 5 Coacting cams 33 and 34 serve to operate the grippers 16 and 20 to cause the transfer of the groups of sheets from the sheet transfer endless carrier 13 to the sheet delivery endless carrier 17. Cams 35 and 36 serve to operate selected sets of grippers 20 on the sheet delivery endless carrier 17 for causing the groups of sheets to be deposited flat upon their inner and outer piles 21 and 22.

From the above description it will be seen that 15 I have provided means whereby the sheets cut from a rapidly traveling web may be collected and transferred to a slower moving delivery carrier for deposit upon their respective delivery piles, thereby ensuring an efficient delivery of the 20 sheets from a high speed web printing rotary press.

It is evident that various changes may be resorted to in the construction, form and arrangement of the several parts without departing from 25 the spirit and scope of my invention, and hence I do not intend to be limited to the particular embodiment herein shown and described, but

What I claim is:

1. In a sheet delivery mechanism, inner and outer delivery piles, a horizontally disposed sheet delivery endless carrier, a sheet collecting rotary carrier, a horizontally disposed sheet transfer endless carrier operable to take the sheets from the sheet collecting rotary carrier and to transfer them to the sheet delivery endless carrier, and means for driving the sheet transfer endless carrier at the surface speed of the sheet collecting rotary carrier and for driving the sheet delivery endless carrier at a lesser surface speed. 5

2. In a sheet delivery mechanism, inner and outer delivery piles, a horizontally disposed sheet delivery endless carrier, a sheet collecting rotary carrier, a horizontally disposed sheet transfer endless carrier operable to take the sheets from the sheet collecting rotary carrier and to transfer them to the sheet delivery endless carrier, and means for driving the sheet transfer endless carrier at the surface speed of the sheet collecting rotary carrier and for driving the sheet delivery endless carrier at a lesser surface speed, the sheet transfer endless carrier extending from a point beneath the sheet collecting rotary carrier to a 20 point beneath the sheet delivery endless carrier. 15
